UNITED STATES PATENT OFFICE.

LOUIS K. JOHNSON AND A. AUGUSTUS LOW, OF BROOKLYN, ASSIGNEES TO
THE ALDEN TYPE MACHINE COMPANY, OF NEW YORK, N. Y.

TYPE-DISTRIBUTING APPARATUS.

SPECIFICATION forming part of Letters Patent No. 340,124, dated April 20, 1886.

Application filed May 12, 1884. Serial No. 131,261. (No model.)

To all whom it may concern:

Be it known that we, LOUIS K. JOHNSON and A. AUGUSTUS Low, citizens of the United States, residing in the city of Brooklyn, in the 5 county of Kings and State of New York, have invented certain new and useful Improvements in Type-Distributing Apparatus, of which the following is a specification.

Our present improvements relate to the form 10 of distributing apparatus set forth in our application for patent, No. 78,535, filed December 6, 1882, in which a duplex bank of conduits or receiving-table is employed, having two groups or divisions of conduits, sufficient 15 in number to accommodate a single font or case of type between them, arranged at suitable opposed angles, back to back, the upper ends of both series being inclined toward each other, so that the receiving ends of both sets of 20 conduits are brought into proximity, and having an independent receiving surface or plate arranged in conjunction therewith to receive and conduct the types of one division into their respective conduits, such receiving plate 25 occupying a plane substantially parallel to that occupied by the other division of the conduits.

Our improvements are the result of investigation and experiment for the purpose of rendering this system of hand-distribution as 30 simple, economical, and practicable as possible. They are designed, more especially, to positively insure the descent of all types through their conduits and their transfer 35 therefrom to the containing-channel "upon the flat" or broad side, and to render the receivers and conduits so that access may be had to them at all times, notwithstanding the positive construction employed to control the descent of the types on the flat.

One feature of our invention in this connection consists in mounting such series of receiving-plates upon the table in such manner that they may be turned back away from the conduit-plate in order to give ready access to the latter when desired.

In our present arrangement the conduits in the right-hand division of each case or bank are provided with the old form of elevated and

overlapping receivers, similar to the manner 50 shown and described in former patents, the only feature of novelty being that each receiver is provided with a transverse guard rail or bar, which prevents the descent of a type unless the latter is resting upon its flat or broad 55 side. The same provision is made in connection with the receiving-plates for the left-hand division of the conduits by gage-projections which descend the proper distance into the receivers.

As hereinbefore indicated, it is to be observed that the types leave the upper receivers and enter into the left-hand division of the conduits at an opposed angle thereto, as in our application before mentioned. In order to 60 guide the types accurately into these conduits and to guard against their turning upon their longitudinal axes or becoming deranged in position, owing to any tendency to rebound after contact with the floor of the conduits, we have 65 devised and arranged guiding and controlling surfaces at or just above the point of incidence between the receivers and conduits, by which the types are transferred evenly and gently to the conduits without danger of derangement or 70 change of relative position. In this connection our invention also includes making these guiding and controlling surfaces adjustable 75 with relation to the lower ends of the receivers, so as to adapt the apparatus to different 80 sizes and styles of types.

For similar reasons the guard rails or projections into the receivers for controlling the passage of the types on their flat sides are made adjustable with relation to the floors of the 85 receivers, and the ends of the receivers themselves are also made adjustable with relation to the floors of the conduits, in order to conform to the other adjustments of the parts for the different sizes of type.

In the accompanying drawings, which represent sufficient of a distributing apparatus of this class to illustrate the application of our improvements, Figure 1 is a top view of a double distributing-table adapted to the simultaneous use of operators stationed centrally upon opposite sides of the apparatus. Fig. 2 is a vertical longitudinal section on plane of

line xx , passing through one of the receivers, formed in the first or upper receiving-plates and showing a type in the act of passing therefrom into the conduit; also showing a vibrating type pusher and forwarder of ordinary construction. Fig. 3 is a vertical section through the upper portion of the duplex conduit-bed and through the receiving-plates, upon a plane which shows the interior of one of the receivers formed in the second or middle receiving-plate, one type being shown as having just entered the conduit and another as passing from the mouth of the receiver and under the guard or check, which prevents the passage of all types unless they rest with one of their broad sides upon the floor of the receiver, and another type as passing under a corresponding guard or check, similar in principle but different in construction, arranged for the same purpose above the receivers upon the right-hand division of the duplex conduit-bank. Fig. 4 is a similar view upon a plane which shows the interior of one of the receivers formed in the third or lower receiver-plate, one type being shown in transition through the curved passage formed by and between the end of the receiver-canal and the adjustable guiding and controlling surface, while another is shown as standing in the mouth of the receiver upon one of its edges or narrower sides, and hence as being prevented from passing through the receiver by the guard or check. Fig. 5 is a vertical elevation of the left division of the duplex conduit-bank, showing the adjustable rack of guiding and controlling fingers in position, the receiver-plates being swung back from the conduit-plate, as indicated by dotted lines in Fig. 2. Fig. 6 is a rear view of the lower or base-plate of the receivers, showing the screws for adjusting the plates with relation to each other to compensate for variations in the sizes and styles of type. Fig. 7 is an end elevation of the receiving plates, showing one of the binding-screws by which the plates are held together, and two of the set-screws by which the upper or first plate is adjusted. Fig. 8 is a cross-section of the conduit-bed of the left division and a plan of the middle or second receiving-plate. Fig. 9 is a similar view of the conduit-bed and the base or third receiving-plate, showing two of the adjustable rests or screws for regulating the position of the receivers with relation to the conduits. Fig. 10 is a view of the upper edge of the rack of transfer or controlling fingers, and Fig. 11 an elevation of the same at right angles to Fig. 10. Fig. 12 is an elevation of the adjustable guard or check used upon the upper receiving-plate, a portion of the latter being shown in section underneath. Fig. 13 is an elevation of one of the guards used in connection with the receivers and conduits upon the right-hand division of the duplex bank. Fig. 14 is a sectional view showing one of the receivers, of cupping form or circular in cross-section, and a correspondingly-shaped guard projecting therein.

In the drawings, the two type-receiving systems or cases C are arranged upon an A-shaped frame or support, A, situated at or near the center of the base-plate or table B. Upon the inclined sides of the support A are arranged a suitable number of conduits, a, which convey the types into the removable containing-channels b, in the usual manner, in which latter the types are forwarded by a reciprocating pusher, P, of similar construction and operation to that shown and described in our application for patent filed December 6, 1882. This is a double comb-push which acts alternately upon the types in the containing-channels situated upon the opposite inclined sides of the duplex bank, and, being made of sufficient length, will answer to forward the types from both cases, C C', with equal facility, thus avoiding the duplication of parts involved in our former duplex distributing-case patented August 14, 1883, No. 282,988.

It will be remembered that the necessary conduits for each "case" are divided upon opposite inclined sides of the frame or support A, and consequently by this arrangement we are enabled to accommodate the receivers, containing-channels, &c., for two cases in little more space laterally than that formerly required for a single case. The economy thus attained in floor-space is obvious, as well as the advantage of dispensing with one power-belt or other source of motion.

In Fig. 1 of the drawings the adjustable guards, &c., are omitted from the case shown upon the upper side of the sheet for the purpose of showing the receivers, &c., more clearly.

The receivers for the conduits upon the right division of each case are elevated slightly and overlap each other, as in our patent of August 14, 1883, No. 282,988, and this side of the case is designed, more especially, for the reception of those denominations of type which are least frequently used, the commoner types being deposited upon the nest of receiving-plates D above.

In order to prevent the descent of the type into the containing channels b, in any other position than upon their flat or broad sides, we arrange guards a', above the floors of the receivers, in such position that the types are obliged to pass thereunder before they can enter the conduits, the space between the floor of the receiver and the lower edge of the guard being just sufficient to allow a particular size of type to pass. These guards are preferably made in the form of continuous rails or bars—one for each tier of receivers—having downwardly-projecting tongues a'', which coincide with and enter the receivers at the required depth. For the double purpose of attaining greater accuracy in adjustment, and to adapt the apparatus for use in distributing different sizes and styles of types, we make these guards a' adjustable. This may be accomplished in a variety of ways, that shown in the drawings consisting in pivoting them between

standards a^3 a^3 upon the conduit-bed and securing them at any desired inclination with relation to the receivers by set-screw nuts a^4 , engaging with the threaded ends of their pivots and binding against the sides of the standards a^3 , as illustrated in Fig. 13. These guards are also preferably made of sufficient width to extend upward and act as shelves or rests to intercept any types that may accidentally be dropped by the operator, and prevent their falling upon the containing-channels and contents below. Such misplaced types are thus retained in a position to be quickly and conveniently removed, and much delay and confusion is thereby avoided. These broad-surfaced guards a' also afford a convenient support for the interchangeable denomination-marks a^5 , which are designed to be used in connection with the receivers. As in a former application for patent for type-setting apparatus, these denomination-marks are adapted to be inserted in any of a series of holes, a^6 , which in the present case are arranged upon the guards or shelves a' at points coinciding with the centers of the receivers. The conduits upon the left division of each bank or case extend upward to the apex of the angle formed by the inclination of the two divisions, and the types are conducted into them from independent receivers d , situated in front of them.

As before mentioned, the principle of construction here involved is substantially the same as that shown in our former application for patent; but we have found that the details of construction can be so modified and improved as to insure more uniform and perfect results. For instance, in the present case we guard effectually against derangement or change, from the required position, of the descending type by positive means, and prevent any sudden concussion or rebound during the actual transition of the types from the receivers to the conduits.

In order to obtain receivers of sufficient width to admit of dropping the types therein quickly and without any great degree of accuracy, we form them in a series of two, three, or more (preferably three) plates, $D' D^2 D^3$, which are superimposed and secured together by binding-screws $d' d^1$, or by other suitable means. The receivers $d' d^2 d^3$ in these plates, when in position in front of the conduits, coincide and communicate consecutively with the conduits, as will be seen by reference to Figs. 1, 8, and 9—that is to say, the receivers in the first or upper plate communicated in order with the first, fourth, seventh, and tenth conduits, those in the middle or second plate with the second, fifth, eighth, and eleventh conduits, and those in the third or base plate with the third, sixth, ninth, and twelfth conduits, respectively, and so on to the end of the series. We are thus enabled to form comparatively wide receivers in the plates, and by making the latter tapering in form toward their upper ends and converging them to-

gether, as shown in Figs. 1, 2, 3, and 4, we practically present them in almost the same plane and in convenient proximity to each other for use.

The receiving-plates D may be attached permanently in position in front of the conduit-plate, if desired; but we prefer to mount them, so that they may be swung back away from the conduits when desired to give access to the latter or to the lower end of the receivers. This may be accomplished in any desired manner, that shown in the drawings consisting in mounting them upon swinging levers or braces $E' E^2$, pivoted to the bed or table of the apparatus, so that the plates may be swung back in the manner indicated by dotted lines in Fig. 2, suitable stops, $e e$, being formed upon the braces E^2 and their bearings E' to prevent too great an extent of motion and to support the parts in the required position.

As before indicated, the lower ends of the receivers descend to the conduits in the form of convex curves $c c$, of sufficient radius to avoid undue abruptness in the transfer of the types to the conduits. The concave finger-pieces f , which act in conjunction with the curved ends $c c$ of the receivers, are preferably attached to a common back or rack, E , (see Figs. 1, 3, 4, 5, 10, and 11,) extending across the upper face of the conduits, upon the floors of which they rest.

It will be noticed that the guides or fingers $f f$ are of different lengths, to conform to the difference in position and elevation between the convex extremities $c c$ of the several receivers' plates, and that the upper plates, $D' D^2$, are formed with recesses or slots $r r$, which allow the guides or fingers $f f$, which act in conjunction with the lower plates, to project or pass through.

The concave fingers or guides $f f$ may be formed to project upward permanently from the floors of the conduits, if desired, or may be attached to the plates themselves; but to attain accuracy in adjustment, and also for the purpose of adapting the device to the distribution of different sizes and thicknesses of type, we prefer to make them adjustable with relation to the ends of the receivers. This is accomplished in the drawings by two fixed screws, $f' f'$, which engage with female threads formed in the ends $f^2 f^2$ of the rack E ; or it may be effected in any other convenient or well-known manner.

For similar reasons the receiving-plates are made adjustable with relation to each other and to the conduits. It will be noticed that the extreme lower ends of the convex receiver-floors project into the conduits slightly in the drawings. This is because all the other parts are shown as set close; or, in other words, adjusted to the size of the smallest type to be used. When it is desired to distribute a type of greater thickness, the receiving-plates D are adjusted bodily away from the conduits the required distance by set-screws $s s$ passing through the conduit-bed and consisting of

gage-rests, against which the receiving-plates D are supported.

The object in adjusting the plates with relation to each other is to regulate the size of the canals or passages formed between them for conducting the types, the under sides of the upper plates being formed with tongues or projections t t, which enter the grooves in the face of the plates next immediately below, and thereby prevent the passage of the type unless of the proper size and upon the flat. In fact, these projections t t constitute the equivalent of the adjustable guards a' a', used in connection with the other receivers and also in connection with the upper receiving-plate, which is provided with a guard-rail, R, Figs. 1, 2, and 12, made adjustable with relation to the floors of the receivers by suspending-screws u u, supported in standards affixed to the face of the plate, and which act in the same manner as the guards a' a' to regulate or prevent the passage of the types.

The adjustment of the plates with relation to each other is effected by loosening the binding-screw d' d' and then setting the bearing-screws v v, Figs. 3 and 7, as desired, and again clamping the plates together in such new position by the binding-screws d' d'.

The bottoms of the receivers d may be made semicircular in cross-section, if desired, for the purpose of more accurately centralizing types that may be dropped therein, in which case the guards a' or t will be correspondingly shaped, as indicated in Fig. 14.

35 In general construction and operation the apparatus herein shown and described resembles that shown and claimed in applications No. 78,535, filed December 6, 1882, No. 144,776, filed October 6, 1884, and No. 156,604, filed 40 February 24, 1885, and we do not seek to claim herein the features that are specifically claimed in either of the applications referred to; but

What we do claim as our invention, and desire to secure by Letters Patent, is—

1. In a type-distributing apparatus substantially such as herein designated, the combination, with a type-receiver, of a guard-rail or gage-plate projecting into the receiver at a point between its widened receiving-surface, upon which the types are dropped, and its narrower portion, through which they pass to the conduits, for the purpose described.

2. In a type-distributing apparatus substantially such as herein designated, the combination, with a type-receiver, of a guard rail or gage plate projecting into the receiver at a point between its widened receiving-surface, upon which the types are dropped, and its narrower portion, through which they pass to the conduits, the said guard or gage plate being made adjustable with relation to the floor of the receiver, for the purpose and substantially in the manner described.

65 3. In a type-distributing apparatus substantially such as designated, a series of superimposed receiving-plates, each formed with re-

ceiving-channels, the lower ends of which form convex curves which conduct the types into conduits placed at an opposed angle to that of the plates, in combination with the said conduits for conducting the type into the containing-channels, substantially in the manner and for the purpose described.

4. In a type-distributing apparatus substantially as described, a series of superimposed receiving-plates, the upper ones of which are formed with tongues or projections which enter a prescribed distance into the type-channels formed in those next immediately below, for the purpose and substantially in the manner described.

5. In a type-distributing apparatus substantially such as described, a series of superimposed receiving-plates, the upper ones of which are formed with tongues or projections which enter the type-channels formed in those next immediately below, the said receiving-plates being adjustable upon and with relation to each other, for the purpose and substantially in the manner described.

6. In a type-distributing apparatus substantially such as described, the combination, with the intermediate conduit-plates which conduct the types to the containing-channels, of a series of superimposed plates formed with receiving-channels, the lower ends of which form convex curves which conduct the types into the conduits which are opposed in inclination to the receiving-plates, which latter are adjustable with relation to the said intermediate conduit-plates, for the purpose and substantially in the manner described.

7. In a type-distributing apparatus substantially such as described, the combination, with the conduits and with the convex ends of the receiver-channels, of concave receiving and guiding surfaces opposed thereto, arranged in connection with the conduits, for the purpose and substantially in the manner described.

8. In a type-distributing apparatus substantially such as designated, the combination, with the conduits for conducting the types to the setter-channels and with the convex receiver-channels, of concave receiving and controlling surfaces or guides which are adjustable with relation to the said receiver-channels, substantially in the manner and for the purpose described.

9. In a type-distributing apparatus substantially such as described, in combination with the conduits for conveying the types to the containing or setter channel, a series of superimposed receiving-plates mounted upon the bed of the apparatus in such manner that they may be swung back away from the said conduits, substantially in the manner and for the purpose described.
